Nelson M. Howard

UNITED STATES PATENT OFFICE.

HENRY J. ASMUS, OF ROCHESTER, NEW YORK, ASSIGNOR TO UNITED SHOE MACHINERY COMPANY, OF PATERSON, NEW JERSEY, A CORPORATION OF NEW JERSEY.

METHOD OF MANUFACTURING SHOES.

1,160,967.

Specification of Letters Patent. Patented Nov. 16, 1915.

Original application filed December 26, 1913, Serial No. 808,878. Divided and this application filed April 7, 1915. Serial No. 19,693.

To all whom it may concern:

Be it known that I, HENRY J. ASMUS, a citizen of the United States, residing at Rochester, in the county of Monroe and State of New York, have invented certain Improvements in Methods of Manufacturing Shoes, of which the following description, in connection with the accompanying drawings, is a specification, like reference characters on the drawings indicating like parts in the several figures.

The invention to be hereinafter described consists in a novel method of shaping the ends of boots and shoes.

In the manufacture of boots and shoes, the upper materials are assembled on a last of suitable shape and form and the shoe is then lasted by drawing the marginal portions of the upper materials over the last and laying the margin thereof over the edge of a sole placed upon the bottom of the last and securing the upper materials in such overlaid position.

In drawing the upper materials about the last and laying the marginal edge portion inward over the last, the resulting fullness or surplus of upper materials causes crimps, plaits, or wrinkles in the marginal edge portions of the upper materials where they overlap the bottom of the last, and these crimps, plaits, or wrinkles extend over the edge of the sole or bend in the upper materials, and to some distance upwardly above the edge of the sole. After the outer sole is applied, these crimps, plaits, or wrinkles will frequently be visible about the end of the shoe.

The present invention, in its broadest aspect, introduces a new procedure in the manufacture of boots and shoes by subjecting the end of the boot or shoe after it has been lasted, and while the parts are held in lasted position, to a shaping or molding pressure prior to the application of the outer sole, which has the effect of molding and shaping the leather at the end of the lasted shoe, and smoothing out the crimps, plaits, or wrinkles.

In another aspect the present invention contemplates subjecting the end of the shoe, after it has been lasted, and while the upper material is secured in lasted position, to the action of heat. This heat will preferably be of such intensity as to cause the leather to shrink and set without injury to the tex-

ture or fiber thereof, so that when the shaping or molding pressure and heat are applied, the leather at the end of the lasted shoe is molded into conformity with the last, and the crimps, plaits, wrinkles and the like, due to the bent condition of the leather, are removed.

A preferred manner of practising the new method consists in applying the shaping or molding pressure to the end of the lasted shoe on opposite sides of the sole edge line to shape and mold the upper materials above the bend or sole edge line into conformity with the shape of the side of the last around the toe, and to lay or flatten the overlying marginal portions of the upper, thus producing a well-defined, smooth bend of the upper along the line of the sole.

My novel method may be practised in any appropriate manner, although under commercial conditions the assistance of mechanical means conformable to the end of the lasted shoe will be utilized as far as possible, substantially as pointed out in application, Serial No. 808,878, filed December 26, 1913, of which the present application is a division. In the apparatus referred to in said application, illustrations of which are furnished herewith as one form of suitable means for carrying out the present method, the shaping or molding pressure at the end of the lasted shoe is effected by relative movement of the lasted shoe and end shaping or molding means conformable to the lasted end of the shoe, and the shaping or molding means is itself heated to the desired degree to shrink and set the leather as the shaping or molding pressure is applied. To effect the desired shaping or molding at the end portion of the lasted shoe, the shaping and molding pressure is applied in a direction generally longitudinal of the shoe to shape or mold the leather about the contour of the lasted end, and substantially transverse thereto to shape or mold the leather on the opposite side of the sole edge line. These shaping or molding pressures may be applied with good results in the sequential order stated, or they may be simultaneously or otherwise applied in carrying out the present method.

In the accompanying drawings:—Figure 1 shows in top or plan view, a lasted shoe, the end of which is positioned opposite suit-

able means for applying the end shaping or molding pressure of the present method, certain parts being shown in section; Fig. 2 is a central longitudinal vertical section of one form of machine by which the present method may be carried out, the toe end of the lasted shoe being shown opposite the end shaping or molding means but out of contact therewith; Fig. 3 is a top or plan view of the toe end of the lasted shoe and the end shaping or molding means positioned for the shaping or molding pressure; Fig. 4 is a view similar to that of Fig. 2, but showing the toe end of the lasted shoe being subjected to the shaping or molding action, some of the parts being broken away; Fig. 5 is a perspective view of one of the end shaping or molding members; Fig. 6 is a side view showing the toe end portion of a shoe after it has been lasted and before it has been subjected to the shaping or molding operation; Fig. 7 is a view similar to that of Fig. 6, showing the toe end portion of the shoe after it has been subjected to the shaping or molding operation; and Fig. 8 is a front end view of the parts represented by Fig. 7.

In that type of shoe in which, during lasting, the upper is turned inwardly over a sole placed upon the bottom of the last, crimps, plaits, or wrinkles occur in the marginal portions of the overlaid upper materials and extend over the turn or bend and above the edge of the sole. This is particularly noticeable at the ends of lasted shoes. Difficulties are experienced in eliminating these defects and properly shaping the ends of the shoe to the last contour, and the overlaid marginal portion of the upper to its seat. Attempts have been made to "iron out" the crimps, plaits, or wrinkles in the upper materials above the turn or bend at the sole edge by a rubbing action, but with a degree of success dependent primarily upon the skill of the operative. In accordance with the method of the present invention, however, a lasted shoe is so treated that the objectionable crimps, plaits, or wrinkles in the end portions of the shoe are eliminated, the leather is shaped or molded in conformity with the last, the bend or turn in the leather at the edge of the sole is smoothed and well defined, the overlaid margin of the upper is molded smoothly to its seat, and the fine lines which are desirable in shoemaking are secured.

A machine which I have found desirable for carrying out the above method comprises a frame preferably formed of a horizontally-extending portion 1 and an upright portion 2 at one end of the horizontally-extending portion. Upon this upright portion may be arranged a molding means comprising preferably two molding members or devices 3, which, when associated together,

are adapted to conform to the heel or to the toe of the shoe. In this instance, a machine is shown as designed for shaping the toe portion of the shoe, but it is apparent that the machine may be readily changed to shape the heel portion.

The molding devices 3, herein shown, which are more particularly adapted for the toe of a McKay shoe or a welt shoe after it has been lasted, each have a curved wall 4 which conforms to one side of the toe from a point at the median line of the shoe to a point preferably beyond the box of the shoe and above the bend or sole edge line. Each molding device preferably also has a portion 5 for engaging the bend of the upper and a portion 6 substantially at right angles to the portion 4 for engaging the inwardly-turned or underlapping stock. Any suitable means may be employed for supporting these molding devices so that they will have a freedom of movement permitting them to conform to the shape of the shoe. In this instance, these molding devices are loosely mounted so that they may be termed to "float" and, to this end, each has ears 7 pivoted at 8 to links 9, which in turn are pivoted at 10 to the upright 2, substantially as set forth in the before-mentioned application. The proximate ends of the dies or molds each have flat portions 11 abutting when the dies are not engaged by the shoe, and also have portions 12 which serve as fulcra on which the dies turn or rock relatively to each other for conforming to the end of the shoe, said portions 12 being at acute angles to the portions 11. From the abutting portions 11, the flanged portions 6 in the illustrated machine incline upwardly toward the outer ends of the molding devices at a slight angle to the plane of movement of the molding devices, so that the flanges may conform to the plane of the sole of the shoe when the latter is supported in position for treatment.

The dies may be normally held in the position shown in Fig. 1, so that their portions 11 abut, yielding means being employed for this purpose. In this instance, a yoked member 13 has rollers 14 at the ends 115 of its two arms for engagement with the inner faces 15 of the two die members 3, said yoked member exerting pressure on the proximate ends of the dies by means of a coiled spring 16 interposed between the upright portion 2 of the casing and the yoked member.

In order to guide the dies 3 in a single plane of operation so that they will have no vertical movement, a guiding means is employed, comprising preferably two walls 17 and 18 arranged in parallel relation and forming a chamber between them, the yoke 13 also being guided between said walls. The upper guide wall 17 may be a removable 130

top wall for the upright portion 2 of the frame of the machine, and may be recessed or cut away to conform to the general curve of the dies or molding devices. The pending front edge of the cut-away or recessed portion may be engaged by the forward ends of the flanged portions 6 so as to limit the movements of the molding devices under the action of the spring 16. 5 The lower guide wall 18 may be employed for heating the dies or molding devices to the desired temperature, suitable for shrinking or contracting the leather, by conduction. I have found about 240° Fahrenheit to give 10 satisfactory results on certain kinds of leather. To this end, an electrical heating coil 19 is arranged below and in close relation to the wall 18, said coil being curved to correspond to the general curve of the 15 two dies, a covering 20 preferably inclosing the heating coil between said wall 18 and a curved wall 21 of a pocket 22 which is formed in the framed portion 2 below the molding dies, in order that the work on 20 the work support may be presented to such dies.

The present method may be conveniently carried out by the character of shaping and molding dies described, and the shrinking 30 and setting effect of the heat may be secured by the application of the heat to the leather through the dies, as described, while the lasted shoe is on the last and suitably supported for the application of the shaping 35 or molding pressure. A convenient form of means for thus supporting the lasted shoe and applying the shaping or molding pressure to the end thereof will now be described.

40 The work support is preferably in the form of a last 23 fitted by means of its jack pin hole to a stem 24 in an inverted position, said stem preferably having screw-threaded engagement with the carriage 25 in order that the last may be raised and lowered on the carriage to locate the plane 45 of the toe bottom parallel with the faces of the flanges 6 of the dies 3. The carriage 25 is preferably movable in horizontal ways 50 or guides 26 formed on the horizontal portion 1 of the frame and extending in a line parallel with the median line through the molding devices in order that the last may be moved toward and from the molding devices. The means for moving this last or 55 work support preferably embodies a cam 27 arranged on a horizontal shaft 28 located vertically below the molding devices and adapted to be turned by any suitable means. 60 This shaft may also have a yoked member 30 guided thereon through the medium of slots 31, the yoke member straddling the cam 27 which moves the said yoke member in opposite directions on the shaft 28. 65 In the yoke member 30, a screw rod 32 is

journaled to turn, said rod having its screw portion 33 coöperating with a slide or nut 34 which extends through a slot in the top of the frame portion 1 and is resiliently connected to the carriage 25, preferably by 70 means of a rod 35 surrounded by a spring 36, and adjustably secured to the carriage 25. The screw rod 32 provides an adjustment in the operating means for accommodating the latter to lasts of different lengths 75 and is preferably turned by a hand piece 37 arranged at one end of the frame portion 1. The elastic connection between the operating means and the carriage 25 is provided in order that the pressure of the last against 80 the molding devices may be resilient or yielding. It is apparent that rotative movement of the cam 27 will move the last toward and from the molding devices in a horizontal plane parallel with the plane of 85 yielding or movement of the molding devices, the last being accommodated within the recessed portion 22, as it approaches and engages the molding devices.

With the end in view of supporting the 90 last and pressing the bottom of the last and the upper thereon against the surfaces 5 and 6 of the flanged portions of the molding devices, means is provided for exerting an upward pressure against the toe portion 95 of the last. In this instance, an engaging member 38 is employed which is preferably covered with a yielding material or pad 39 to prevent injury to the upper on the last. This engaging device may be 100 adjustably arranged on a rod or vertically movable member 40 which near its upper end is guided through a collar 41, the latter in turn being resiliently or yieldingly supported for slight lateral movement, and to 105 this end carrying a horizontally-extending stem 42 guided in a perforated lug 43 and pressed in one direction by a coil spring 44 which surrounds the stem and abuts at one end against the collar 41 and at the other end against the lug 43. This supporting rod 40 may also be operated by the cam 27, and to this end, it carries at its lower end a yoke 45 which straddles the shaft 28 to be 110 guided vertically by the latter and also straddles the cam 27 in order that the said cam may engage the yoke 45 to lift the engaging device 38 after said cam engages the yoke 30 to shift the last 23 toward the molding devices. A spring 46 surrounds the 115 rod 40 between the yoke 45 and the collar 41 and acts to depress the engaging device 38 and the rod 40 after the last has been moved away from the molding devices.

When the shoe is lasted, as hereinbefore 120 noted, the marginal portions of the upper material is drawn and laid over the inner-sole placed upon the bottom of the last and secured in lasted position as by tacks b. This is typified in Fig. 1, wherein it will 125

be seen that in the marginal portions of the upper materials of the lasted shoe, there are more or less crimps, plaits, or wrinkles, and that these extend over the turn or bend 5 of the upper at the edge of the innersole and last, as illustrated, for example, in Fig. 6.

A lasted shoe, such, for instance, as that above described and illustrated by Fig. 1, 10 which typifies a McKay shoe, is placed in an inverted position upon the adjustable support 24 so that the toe points toward the molding devices, the parts being adjusted, of course, to the size of the shoe on which 15 the machine is to operate. By operating the shaft 28 and cam 27, the last and the shoe are forced against the molding devices and particularly against the faces 4 thereof near the abutting ends of the molding 20 devices. This causes the latter to rock on their pivots 8, which also shift to permit the molding devices to conform to the shape of the toe. After a certain pressure has been exerted upon the parts, the engaging 25 member 38 moves upwardly to force the underlapping stock of the upper against the face 6 and the face 5 of the flange. The molding devices are preferably heated to a sufficiently high degree to cause the leather 30 to shrink and become set, so that, as the pressure is exerted simultaneously upon the whole end of the shoe, including the turn or bend, and on opposite sides of the latter, the toe is molded into the shape of the molding 35 devices which also conform to the shape of the last. This operation removes wrinkles, plaits, or crimps in the toe, due to the upper being turned inwardly or under and, at the same time, gives the toe the fine lines 40 which are desirable in shoemaking.

The illustrated machine has been designed more particularly for molding the toes of McKay shoes and welt shoes. By reducing the size of the flanges 6 on the molding 45 devices, the same machine may be employed for molding the toes of "turn" shoes. It is apparent, also, that the machine may be adapted for molding the heel portions of shoes, and such a heel portion molding machine has particular advantages when used 50 with a "turn" shoe, as it tends to give a definite form to the heel counter, it being well known that heel counters of "turn" shoes cannot be molded before being inserted in 55 the shoes, as is usually done in the manufacture of McKay shoes and in the manufacture of many welt shoes.

The effect of the present method in subjecting the end of the lasted shoe to a shaping or molding operation, is well indicated by a comparison of Figs. 6, 7 and 8, wherein Fig. 6 shows the lasted shoe as it appears 60 after the lasting operation when the marginal portion of the upper has been secured in overlaid or lasted position, and before treat-

ment by the present method. In this Fig. 6, as well as in Fig. 1, the condition of the shoe parts is such that the leather only approximates to the contour of the end of the last, and crimps, plaits, or wrinkles in the 70 leather extend from the overlaid marginal portion of the upper, and over the bend or turn at the edge of the inner sole or last. Figs. 7 and 8 show the same lasted shoe after 75 the shaping or molding operation of the present method has been performed, and it will be apparent that the leather has been shaped or molded, with substantial accuracy to the contour of the last, and that the crimps, plaits, or wrinkles have been eliminated from the bend or turn, as at *c*, as well as from the side portions of the end as at *d*, thus presenting the fine, smooth lines desired. A further advantage from use of the invention on a McKay shoe is that the shoe 80 is in a better condition to receive the outer sole, as the latter may lie flat against the underlapping stock of the upper in proximity to the sole edge line so that no space is provided between the shoe upper and the 85 lower or outer sole.

Where, as in the present illustration, the shoe is held in lasted position by tacks, the shaping or molding operation on the bottom of the shoe is preferably extended only to those portions of the overlaid upper materials between the line of tacks and the bend or turn at the edge of the sole and last, substantially as indicated in Fig. 3, and in case 90 of welt shoes, the shaping or molding of the upper materials may be extended to the angle between the feather and lip of the welt shoe innersole.

What is claimed is:—

1. The method of shaping the ends of 105 boots and shoes after they have been lasted and the upper materials secured in lasted position, which comprises subjecting the leather simultaneously at opposite sides of the end of the lasted boot or shoe to a shaping or molding pressure to press the leather into conformity with the last.

2. The method of shaping the ends of 110 boots and shoes, which consists in applying a shaping or molding pressure simultaneously at opposite sides of the end portion of the boot or shoe after it has been lasted and while the parts are secured in lasted position prior to the application of the outer sole and simultaneously heating the end of the lasted shoe to remove crimps and wrinkles.

3. The method of shaping the ends of 115 boots and shoes, which consists in applying a shaping or molding pressure to the end portion of the boot or shoe at opposite sides of the bend or sole edge line after the boot or shoe has been lasted and the parts secured in lasted position prior to the application of the outer sole, and simultaneously 120

subjecting the leather at the end of the lasted boot or shoe to the action of heat of sufficiently high temperature to shrink the leather.

5. The method of shaping the ends of lasted boots and shoes, which comprises applying a shaping or molding pressure and a leather shrinking heat to the end of the shoe while the upper materials are secured 10 in lasted position.

5. The method of shaping the ends of boots and shoes after they have been lasted, which consists in applying to the end of the lasted shoe after the parts are secured in 15 lasted position a shaping or molding pressure extending uninterruptedly from one side of the bend or sole edge line to the other, and shrinking the leather by heat during the application of the shaping or 20 molding pressure.

6. The method of shaping the ends of lasted boots and shoes, which consists in applying a shaping or molding pressure simultaneously to the opposite sides of the 25 end of the lasted boot or shoe at one side of the sole edge line substantially parallel to the shoe bottom after the parts are secured in lasted position, and a shaping or molding pressure to the end of the boot or 30 shoe at the opposite side of the sole edge line in a direction substantially perpendicular to the shoe bottom.

7. The method of shaping the ends of lasted boots and shoes, which consists in applying a shaping or molding pressure to the end of the lasted boot or shoe at one side of the sole edge line substantially parallel to the shoe bottom after the parts are secured in lasted position, and a shaping or 35 molding pressure to the end of the boot or shoe at the opposite side of the sole edge line in a direction substantially perpendicular to the shoe bottom.

lar to the shoe bottom and simultaneously with the application of said shaping and molding pressures, shrinking and setting 45 the leather by heat applied at the end of the boot or shoe.

8. The method of shaping the ends of boots and shoes after they have been lasted, which consists in applying a shaping or 50 molding pressure simultaneously over an extended portion of the upper materials at opposite sides of the end of the boot or shoe while the upper materials are secured in 55 lasted position.

9. The method of shaping the ends of lasted boots and shoes, which consists in applying a shaping or molding pressure simultaneously to the two sides and the end of the toe of a lasted boot or shoe at one 60 side of the sole edge line after the parts are secured in lasted position, and a shaping or molding pressure simultaneously to the two sides and the end of the toe of the lasted boot or shoe at the opposite side of the sole 65 edge line.

10. The method of shaping the ends of lasted boots and shoes, which consists in applying a shaping or molding pressure simultaneously to the two sides and the end 70 of the toe of a lasted boot or shoe at one side of the sole edge line after the parts are secured in lasted position, and a shaping or molding pressure simultaneously to the two sides and the end of the toe of the 75 lasted boot or shoe at the opposite side of the sole edge line, and simultaneously with the application of said shaping and molding pressures, shrinking and setting the leather by heat applied to the end of the boot or 80 shoe.

In testimony whereof I have signed my name to this specification.

HENRY J. ASMUS.
